UNITED STATES PATENT OFFICE.

EVERETT D. ROCK, OF NUTTSVILLE, VIRGINIA.

VARIABLE SAWMILL-FEED.

No. 825,865.

Specification of Letters Patent.

Patented July 10, 1906.

Application filed December 6, 1905. Serial No. 290,633.

To all whom it may concern:

Be it known that I, EVERETT DORSIE ROCK, a citizen of the United States, residing at Nuttsville, in the county of Lancaster and 5 State of Virginia, have invented new and useful Improvements in Variable Sawmill-Feed, of which the following is a specification.

This invention relates to an improved sawmill-feed, and has for its object to provide a 10 novel construction and arrangement of parts in a machine in which a combined variable-feed and reversing mechanism is operated directly from the main driving-shaft without the interposition of belts and which provides 15 for a variable movement of the sawmill-carriage in either the forward or backward movement thereof and for the reversal of the movement of said carriage through the medium of a single friction-wheel.

20 The invention has for its object to provide a novel arrangement of coöperating frictionally-engaged members the degree of contact-pressure between all of which may be simultaneously varied.

25 The invention also has for its objects a novel construction of mechanism for moving the friction-wheel which controls the rate and direction of movement of the carriage and a novel mechanism for forcing said friction-wheel into contact with the face-wheel which 30 drives the same with greater or less force or for entirely removing the said friction-wheel from contact with such face-wheel.

In addition to the above-enumerated objects of the invention further objects reside 35 in certain novel details of construction and combination and operation of parts, all of which will be more clearly understood from the detailed description to follow.

40 The invention is illustrated in the accompanying drawings, in which—

Figure 1 is a plan view of the variable-feed mechanism mounted upon the husk frame. Fig. 2 is a detail perspective view showing 45 the various parts of the mechanism for operating the friction-clutch, and Fig. 3 is a sectional detail view of part of the operating mechanism.

Referring now to the drawings, 1 indicates 50 a husk-frame on which is mounted in bearings 2 a mandrel 3, having secured on one end a circular saw 4 and on its other end a belt-pulley 5, by means of which said mandrel may be driven by a belt, as usual. Secured 55 on the shaft 3 intermediate its ends is also a beveled metal friction-pulley 6, which is in

peripheral contact with an oppositely-beveled paper friction-pulley 7, secured on a shaft 8, which is slidably mounted for longitudinal movement in bearings 9, supported 60 on supplemental frame members 10 of the frame 1. The shaft 8 has mounted on one end a metal face-wheel 11, the outer face of which is adapted to be frictionally engaged by a paper friction-wheel 12, keyed to and 65 slidably on a shaft 13. The shaft 13 is mounted in pivoted bearings 14 15, respectively, the bearing 14 being mounted on a transverse frame member 16 and the bearing 15 being mounted in a support 17, which 70 is pivotally mounted at its lower end on the husk-frame, as indicated at 18. At one end the shaft 13 has secured thereon a pinion 19, which is in mesh with a large gear-wheel 20, secured to which is a beveled gear 21. The 75 gear 20 and beveled gear 21 are secured to a short shaft 22, which is suitably mounted in the husk-frame.

23 indicates a shaft also suitably mounted in the husk-frame and projecting laterally 80 beyond the same and having on its outer end a gear 24, which is adapted to mesh with a rack-bar (not shown) carried by the sawmill-carriage, as usual. The shaft 23 has secured on its inner end a beveled gear 25, which is 85 in mesh with the beveled gear 21.

The mechanism for moving the friction-wheel 12 over the face of the wheel 11 will now be described. Supported on the frame 1 is a stand 26, in which is mounted for rotation a rod 27, having secured on its lower end a crank-arm 28, provided with an integral crank-pin 29, which engages and works in a slot 30 of a lever 31. Said lever has pivotally connected to one of its ends a link 32, 95 which in turn is pivotally connected at its outer end to the frame 1. The opposite end of the lever 31 is pivotally connected to a bar 33, which has an outer forked end 34. This outer forked end embraces and has a pin-and-groove connection with a hub 35, connected to the inner face of the friction-wheel 12. The rod 27 has an angular projecting arm 36, to the outer end of which is pivotally connected a handle 37. By throwing this handle in one direction or the other the rod 27 is also correspondingly turned and through the medium of the crank-arm 28 and lever 31 will move the bar 33 longitudinally in one direction or the other. The latter bar having its forked end 34 connected with the hub 100 of the friction-wheel 12, as described, will 105 of the friction-wheel 12, as described, will 110

pull said wheel along the shaft 13 toward or from the center of the face-wheel 11. As will be seen, the nearer the wheel 12 approaches the center of the face-wheel 11 the more slowly the former will be rotated, and if the wheel 12 is carried past the center of the face-wheel 11 the direction of rotation of the former will be reversed. While in its position at either side of the center of the face-wheel 15 the friction-wheel can be made to occupy any desired position between the periphery and center of the face-wheel, so that the movement of the sawmill-carriage effected through the medium of the gear 24 can be varied as desired in either direction of movement of said carriage, the variable feed or movement and the reversal of movement being effected, as will be seen, through the medium of a single friction-wheel 12, coöperating with the face-wheel 11. It is desirable that the frictional driving member described shall be in firm contact while the machine is actually used in sawing wood and in less firm contact when the machine is running without sawing, and it is, moreover, desirable to remove the friction-wheel 12 from contact with the face of the wheel 11 to stop relative movement of the parts. To effect this adjustment I employ the mechanism which will now be described. Secured on the upper side of the handle 37 is an eyebolt 38, in which is pivotally mounted a bail 39, the outer ends of which embrace and are pivotally secured to a sleeve 40. The sleeve 40 is provided with an annular groove 41, in which is rotatably mounted a ring 42, having on diametrically opposite sides lugs 43.

44 indicates a throw-lever having an outer forked end 45, said forks being recessed or bifurcated at their outer ends, as indicated at 46, to embrace the lugs 43. The throw-lever 44 is integrally or otherwise connected with a rock-shaft 47, extending longitudinally of the frame 1 and supported in bearings 48 thereon and having at its outer end an integral arm 49, extending at right angles thereto. This arm is pivotally connected to one end of a strap 50, which at its outer end is pivotally connected to the upper end of the support 17. The throw-lever 44 extends upwardly from its point of connection with the rock-shaft 47 to the sleeve 40. It will now be seen that if the handle 37 is lowered the sleeve 40 will be correspondingly lowered, 55 said sleeve sliding over the rod 27, and the outer forked end of the throw-lever will be carried down by its engagement with the lugs 43 of the ring 42, which latter is mounted on the sleeve 40, and this operation will result in turning the rock-shaft 47, thereby through the medium of the arm 49 and strap 50 throwing the support 17 inward and causing the friction-wheel 12 to frictionally engage the face of the wheel 11. The wheel 12 can 60 be made to engage the face of the wheel 11

more or less firmly, according to the downward pressure applied to the handle 37. As the shaft 8, on which the face-wheel 11 is mounted, is also slideable the pressure applied to the wheel 11 will also operate, owing to the incline of the pulley 6 and beveled friction-pulley 7, to cause these latter parts to engage more firmly, and, as in the case of the friction-wheel 12 and wheel 11, the engagement between the pulley 6 and the beveled friction-pulley 7 will be greater or less according to the pressure applied to the handle 37. By raising the handle 37 a greater or less extent the friction members may be caused to engage less firmly, so as to decrease the amount of the friction at the bearings of the various shafts, and by raising the handle 37 a sufficient extent the friction-wheel 12 may be entirely removed from contact with the face of the wheel 11 and the movement stopped. The provision of means for relieving the pressure of frictional contact between the friction members is a very important part of the invention, as by relieving undue pressure on the boxes or bearings when the mill is not feeding said boxes or bearings will remain cool, even if through neglect they should not be oiled often.

In order to hold the handle 37 in any desired adjustment, I provide on the upper end of the rod 27 a quadrant 51, having notches 52, which are adapted to be engaged by a spring-latch device 53, carried by the handle 37.

100 It will be seen that I entirely dispense with belt-gearing. The arrangement of the friction-pulley on the mandrel and of the beveled friction-pulley which works against it tends to even up the pressure on the mandrel-boxes, caused by the strain on the driving-belt working on the pulley 5, and keeps the boxes from wearing out of true.

I claim—

1. In combination with a driven mandrel, a beveled friction-pulley mounted thereon, a longitudinally-movable and rotatable shaft, a beveled friction-pulley and a face-wheel mounted thereon, said beveled friction-pulley frictionally engaging the periphery of said friction-pulley and being in the same plane as the latter, a driven shaft, and means for driving said shaft from said face-wheel comprising a shaft, a friction-wheel keyed thereon and adapted to frictionally engage said face-wheel, means for moving the said latter shaft toward and from said face-wheel, and means for moving said friction-wheel transversely over the face of said face-wheel.

2. In combination with a driven mandrel, a variable-feed device comprising a face-wheel, means for rotating said face-wheel from said mandrel, a driven shaft, means for driving said shaft comprising a pivotally-mounted shaft, a friction-wheel keyed on said

110 115 120 125 130

pivotsly-mounted shaft and adapted to frictionally engage said face-wheel, a rotatable rod, a handle pivotally associated therewith for turning the same, a crank on said rod having a pin, a bar operatively associated at one end with said friction-wheel, a pivotally-mounted lever pivotally connected to said bar and having a slot receiving said pin, whereby the turning of said rod will cause said friction-wheel to move transversely over the face of said face-wheel, and mechanism comprising a rock-shaft operatively connect-

ing said handle and said pivotally-mounted shaft whereby upon raising or lowering said handle said pivotally-mounted shaft may be moved toward or from said face-wheel. 15

In testimony whereof I have hereunto set my hand in presence of two subscribing witnesses.
